UNITED STATES PATENT OFFICE.

HORACE D. HONEY, OF HOLYOKE, MASSACHUSETTS, ASSIGNOR TO THE NATIONAL BLANK BOOK COMPANY, OF SAME PLACE.

INVOICE OR SCRAP BOOK.

SPECIFICATION forming part of Letters Patent No. 437,493, dated September 30, 1890.

Application filed November 25, 1889. Serial No. 331,415. (No model.)

To all whom it may concern:

Be it known that I, HORACE D. HONEY, of Holyoke, in the county of Hampden and State of Massachusetts, have invented a new and useful Improvement in Invoice or Scrap Books, of which the following is a specification, reference being had to the accompanying drawings, forming a part thereof.

My invention relates to the construction of invoice or scrap books; and it has for its object to provide a book of this nature in which increased strength and durability and cheapness in construction will be combined.

To this end the invention consists in the book constructed as hereinafter fully described, and particularly pointed out in the claims.

Referring to the drawings, in which like letters designate like parts in the several figures, Figure 1 is a diagram illustrating the manner in which the book is formed. Fig. 2 is a view in perspective of one of the guard-strips. Fig. 3 is an end view of the completed book. Fig. 4 is a diagram illustrating the preferred manner of securing the sections together at their rear side.

The several sections of the folded sheets which make up the book are designated by the letter *a*. *b* designates the guard or filling-strips, which, by being inserted between the sections *a*, fill out the back of the book, said strips being preferably composed of narrow strips of paper-board, united by stitching, as represented in Fig. 2, and *c* designates the book-cover.

Various ways of securing the guard-strips *b* between the sections *a* have heretofore been devised, but each of said methods has been found to be objectionable either because of its cost in manufacture or because the book has lacked strength and durability. One of the most common methods is to employ an independent binding-sheet, which is folded or crimped in such manner as to extend between each of the sections *a* and to receive within each of its folds one of the guard-strips. The objection to such method is that the difficulty experienced by the operator in properly starting and manipulating such independent sheet in building up the book necessitates comparatively slow work by the operator and adds

materially to the cost of manufacture of the book. Moreover, there being nothing to tie such independent sheet and the guard-strips inclosed thereby to the sections *a*, except the stitching at the back of the book, a defect in said stitching will in time permit said sheet and strips to work out of place, thus greatly shortening the effective life of the book.

In constructing the book according to my invention, I utilize the uppermost leaf of the bottom section *a* as a binding-sheet, as clearly shown in Fig. 1, said leaf being folded back upon itself, as shown at 1, to receive the first guard-strip *b*, then again folded back in the opposite direction to receive the next section *a*, as shown at 2; again folded, as shown at 3, to receive the second strip *b*, and so on until the entire leaf has been consumed by said successive folds, as shown at the point 4 in Fig. 70 3, at which point the uppermost leaf of the section *a*, last inserted, is utilized in the same manner as a binding-sheet until a sufficient number of sections and guard-strips have been utilized to make the book of the desired thickness. Such building up of the book can be performed very rapidly by the operator, for the reason that the binding-sheet is firmly held in a true position at all times, and no efforts to keep it in such position are required. 80 As the successive sections *a* are placed in position they are connected by stitches to the usual tapes *d* and cords *e*, as represented in Fig. 4, or may be secured by any of the methods usually employed in book-sewing. 85

By thus utilizing a leaf of one of the sections *a* as a binding-sheet, I not only effect a considerable saving in the cost of manufacture, as just stated, but I provide a stronger and more durable book, for the reason that the sections *a*, strips *b*, and the binding-sheet are thus tied together very firmly independently of the stitching, and are not dependent upon the perfection and strength of the latter for their durability.

I do not wish to limit myself to the particular form of guard-strip, nor to the method of stitching said strips and the sections *a* together, (herein shown,) as other forms thereof can be employed within the spirit of my invention.

Having thus fully described my invention,

what I claim, and desire to secure by Letters Patent, is—

1. The invoice or scrap book herein described, comprising a series of sections of folded leaves of paper, a series of guard-strips interposed between said sections, and a binding-sheet having a series of folds to receive said guard-strips, said binding-sheet being composed of one of the leaves of one or more of said folded sections, substantially as set forth.
2. In a scrap or invoice book, the combina-

tion of the sections *a*, composed of folded leaves of paper, with the guard-strips *b* interposed between such sections, the uppermost leaf of the lower section *a* being folded, as described, to receive therein said guard-strips and the rear edges of the remaining sections, substantially as and for the purpose described. 15

HORACE D. HONEY.
